HOUSING FOR AN AQUARIUM HEATER AND FILTER

Walter Sesholtz, Park Ridge, N.J., assignor to Sternco
Industries, Inc., Harrison, N.J., a corporation of New
Jersey

Filed Sept. 27, 1968, Ser. No. 13,756

Term of patent 14 years

Int. Cl. D23—01, 03

U.S. Cl. D23—4

FIG. 5

FIG. 4

FIG. 6

FIG. 1 is a perspective view of a housing for an aquarium heater and filter heater showing my new design.

FIG. 2 is a side elevational view thereof looking from the right side of FIG. 1.

FIG. 3 is a side elevational view thereof looking from the left side of FIG. 1.

FIG. 4 is a rear view thereof.

FIG. 5 is a top plan view thereof.

FIG. 6 is a bottom view thereof.

The fragmentary portion of the aquarium and indicia are shown in broken lines for illustrative purposes only.

I claim:

The ornamental design for a housing for an aquarium heater and filter, as shown and described.
